UNITED STATES PATENT OFFICE.

LAWRENCE JENSEN, OF WICKLIFFE, OHIO.

WALL-PAPERING MACHINE.

1,331,436.

Specification of Letters Patent. Patented Feb. 17, 1920.

Application filed June 23, 1919. Serial No. 306,012.

To all whom it may concern:

Be it known that I, LAWRENCE JENSEN, a citizen of the United States, residing at Wickliffe, in the county of Lake and State 5 of Ohio, have invented new and useful Improvements in Wall-Papering Machines, of which the following is a specification.

This invention comprehends the provision of a wall papering machine, which is simple 10 in construction, capable of being easily handled and manipulated to permit of its use by persons inexperienced in the art of paper hanging.

The invention embodies among other features, a roll mounted for rotation upon one 15 end of a handle, the roll being adapted to be moved over the wall or ceiling during the application of the paper thereto, moving the paper against the wall during its course 20 of travel.

Other objects of importance reside in the provision of means for securing one end of the strip of paper to be applied, to the roll while the latter together with the strip of 25 paper is being elevated to the starting point either upon the wall or ceiling.

In carrying out my invention, I make use of a swingingly mounted yoke, designed to be positioned in the corners and the angle 30 between the wall and the ceiling for applying the paper at such points where the roll cannot be used, means being employed to maintain the yoke fixed relative to the handle in any given position.

35 The nature and advantages of the invention will be more apparent, when the following detailed description is read in connection with the accompanying drawings, the invention residing in the construction, 40 combination and arrangement of parts as claimed.

In the drawing forming part of this specification like numerals of reference indicate similar parts in the several views, and 45 wherein:—

Figure 1 is a front elevation of the machine constructed in accordance with my invention.

Fig. 2 is a side elevation showing the 50 manner of using the invention for applying the paper to the wall.

Fig. 3 is a similar view partly in section showing the position of parts when the device is used for applying a strip of paper to 55 the ceiling.

Fig. 4 is a perspective view of the yoke.

Referring more particularly to the drawing in detail A indicates a frame which may be constructed from any suitable material, preferably metal and of U-shaped formation. The frame is formed with a socket 10 adapted to accommodate one end of the handle 11, the latter being hollow for a purpose to be hereinafter set forth. Journaled for rotation between the parallel limbs 12 of the frame A is a roll 13 to which one end of the strip of paper B is temporarily secured, so that the roll and paper may be elevated to the desired location from which it is to be applied to either the wall or ceiling. A covering of soft rubber or other suitable material 13' surrounds the roller 13. For this purpose, I employ a bar 15 mounted for sliding movement between the parallel portions 12 of the frame, while depending from the bar 15 is a stem 16 which is partly received within the socket 10. The stem 16 is formed with a shoulder 17 against which one end of a coil spring 18 bears, the opposite end of the spring bearing against the 80 adjacent extremity of the handle 11 whereby the spring 18 functions to normally maintain the bar 15 in advanced position against the roll. As shown the spring 18 is completely housed within the socket 10. Manifestly, when the bar 15 is engaged with the roll, one end of the paper B is effectively engaged between the roll and the bar for the purpose above mentioned, the roll being held against rotation. However, when it is 90 desired to permit of rotation of the roll, the bar 15 is moved away from the roll and held in spaced relation thereto. For this purpose, I arrange a rod 20 within the handle 11, the rod having suitable connection with the adjacent end of the stem 16, the opposite end of the rod 20 being offset as at 21 and operated within a slot 22 of the handle. The offset extremity 21 of the rod provides a hand hold by means of which the bar 15 100 can be retracted against the tension of the spring 18, and when in this position a ring 23 pivoted upon the handle 11 is moved to engagement with the offset extremity 21 to hold the parts in their given position.

Pivoted upon the opposite sides of the frame A are the parallel arms 24 of what I term a yoke, the latter including a cross piece 25 connecting the forward extremities of the arms 24. The cross piece 25 is preferably of triangular formation in cross section, and between two sides thereof a strip

of rubber or the like indicated at 26 is clamped. The yoke is primarily intended to be used in applying the paper to the wall or ceiling adjacent the corners, or in the angle between the wall and the ceiling where it is impossible to position the roller. However, the yoke is susceptible for use in other capacities which materially add to the efficiency of the machine as a whole. In this connection it is to be understood that the yoke may be swung in any angular position with respect to the roll 13, and held fixed in this given position by tightening the nut 27 upon the threaded projections 28 on which the yoke is pivoted. When the yoke is not utilized for applying the paper to the corners as above stated, it is used in the capacity of a paper support, the strip B being arranged or extended across the yoke and resting thereagainst whereby the yoke serves to hold the strip B spaced from the wall as the roller 13 is being moved thereover during the application of the paper.

In practice, the bar 15 is retracted against the tension of the spring 18 and held in this position in the manner above described. The yoke may be swung into any position out of the way, to permit free access to be had to the roll 13, so that the free end of the strip B may be partly wound about the roll. The rod 20 is then released to permit the bar 15 under the influence of the spring 18 to effectively engage this end of the paper, and prevent rotation of the roll 13, so that these parts are held fixed relatively while the roll is being elevated to a position for use. Prior to the raising of the roll to the position for use, the yoke is swung upon its pivot to the position illustrated in Fig. 2, which position is below the roll 13 when a strip of paper is being applied to the wall. The yoke in this position holds the strip B spaced the proper distance away from the wall as will be readily understood. With the parts arranged in the manner disclosed in Fig. 2, the machine is ready for use, and the bar 15 is then again retracted and held in spaced relation to the roll to permit rotation of the latter. The roll is then moved downwardly over the wall applying and smoothing the paper thereagainst during its course of travel, the yoke moving in advance of the roll to hold the paper spaced from the wall as stated.

When applying a strip of paper to the ceiling, the swingingly mounted yoke assumes the position illustrated in Fig. 3, in which position the paper is supported by the strip of rubber 26 in proper relation to the ceiling. After the strip has been applied to both the ceiling and the wall, the yoke may be swung to the proper position with respect to the handle 11, to permit the

rubber strip 26 to be conveniently positioned in the corners, where the roll cannot be arranged, for the purpose of securing the free ends of the paper to their respective parts.

While I have shown and described what I consider the preferred embodiment of the invention, I desire to have it understood that what is herein shown is merely illustrative, and that I do not limit myself in these specific details, as such changes may be resorted to when desired as fall within the scope of what is claimed.

What I claim is:—

1. A machine of the character described comprising a frame, a roller journaled in said frame, a hollow handle depending from said frame, a bar arranged transversely of the frame and slidably mounted upon the side thereof, a rod depending from the bar and slidably fitted in said handle, a ferrule projecting from one end of the handle, a collar formed on said rod, a coiled spring encircling said rod and arranged in said ferrule, and engaging the handle and said collar for normally holding the element in engagement with said roller, and means for holding said element in spaced relation to said roller against the tension of said spring.

2. A machine of the class described comprising a frame, a roller journaled in said frame, a yieldably mounted element arranged to normally engage said roller to prevent rotation thereof, a handle, a yoke freely pivoted on the frame to assume a dependent position therefrom, or any angular position with relation thereto, and means for holding the yoke in a given position.

3. A machine of the character described comprising a frame, a handle therefor, a roller journaled on the frame, a yieldably mounted element normally engaging said roll, threaded studs projecting from the frame, a yoke freely pivoted on said studs and adapted to assume a depending position with regard to the frame, or an angular position with respect thereto, and nuts threaded on said studs and adapted to hold said yoke in any given position with respect to the frame.

4. A machine of the class described comprising a frame, a roller journaled on said frame, a handle, a yoke freely pivoted on said frame, means for holding the yoke in any given position with respect to the frame, the transverse bar of said yoke being of substantially triangular formation in cross section, and a strip of rubber or other yieldable material clamped between the sides of said cross piece, as and for the purpose specified.

In testimony whereof I affix my signature.

LAWRENCE JENSEN.
